UNITED STATES PATENT OFFICE.

CHARLES W. BREWSTER, NEW YORK, N. Y., ASSIGNOR TO THE BREWSTER-GOLDSMITH CORPORATION, INC., A CORPORATION OF NEW YORK.

SPARK-PLUG.

1,390,014.

Specification of Letters Patent. Patented Sept. 6, 1921.

Application filed June 9, 1919. Serial No. 302,734.

To all whom it may concern:

Be it known that I, CHARLES W. BREWSTER, a citizen of the United States, and a resident of New York, in the county and State of New York, have invented a new and useful Improvement in Spark-Plugs, of which the following is a specification.

My improvement relates to spark plugs. It has for its object to provide a new and improved spark plug of great durability, and one capable of withstanding the high temperatures and strains of high compression motors. It consists of the novel devices and combinations herein set forth.

15 In the accompanying drawings forming part of this specification I have shown my improvement in its preferred form, and also some modifications of such form.

20 Referring to the drawings, Figures 1, 2 and 3 illustrate a preferred form of my improvement in which Fig. 1 is a central longitudinal section through the spark plug, and Figs. 2 and 3 are cross-sections on the lines 2—2 and 3—3, respectively, of Fig. 1, viewed as shown by the arrows. Figs. 4, 5 and 6 represent central longitudinal sections through modifications.

25 Referring to the specific embodiment disclosed in Figs. 1, 2 and 3, 1 is the electrode of my improved spark plug, having preferably a reduced portion at its lower end as shown. It is mounted in a spindle 2 in the usual way. 3, 4 and 5 represent insulating material such as mica. The electrode 1 passes through two chambers closed to the atmosphere, an upper chamber 6 and a lower chamber 7. The upper chamber 6 is formed by a hollow cylindrical piece 8 having its lower walls inwardly converging as at 9 to form a small circular opening 10 around the body of the electrode. Piece 8 is held in place by a follower 11. 12 is a nut and 13 a collar.

30 14 is a hollow conical shaped piece or ring made of compressible material such as a soft metal like brass. It closely surrounds the mica and is forced against it and piece 5 in the manufacture of the spark plug by means of the follower 11 to form a tight joint 35 around the spindle to prevent the escape of gases from the chamber 6.

35 The lower outer portion of the spark plug consists of a body 15 provided at its upper end with screw threads meshing with the 40 corresponding screw threads on the fol-

lower 11 and provided at its lower end with the usual screw threads 16. The body 15 is closed at its lower end by metallic walls 17 shaped somewhat like an hour glass, that is, with its lower surface sloping outwardly and downwardly from the center, and its upper surface sloping outwardly and upwardly from the center. There is an opening 18 at the center surrounding the end of electrode 1, and the inner wall of 45 which forms the second electrode. The electrodes may be made of any suitable material. The hour glass piece 17 has one or more ports 23 in it, four in number, as shown in Figs. 1 and 3. These preferably extend upwardly and outwardly, as shown, for a purpose to be shortly described. Body 15 forms a chamber 19 surrounding the chamber 6 and intended to act as a cooling chamber. This cooling chamber may be of 50 any suitable construction and may be supplied in any way with any suitable cooling fluid. As shown, and preferably, it is an open chamber supplied with air from the atmosphere and for this purpose it is provided with ports 20 connecting with the atmosphere for the circulation of cooling air either naturally or under forced draft, in order to assist in dissipating the heat generated in the inner parts. Part 8 is also preferably made of some suitable metal with 55 high heat conducting capacity such as brass, to assist in the dissipation of heat.

55 21 is the usual cylinder gasket and 22 an integral extension or collar on the spindle 2 for supporting the mica. It will be understood that the mica is tightly held and compressed between the various parts of the spark plug to afford good insulation and 60 tight joints.

65 Chamber 7, commonly called by me the scouring chamber, is provided with surfaces shaped so as to receive that part of the blast of the explosion which comes through ports 23, and direct it against the central electrode and through the spark gap 18. These surfaces, as shown in Fig. 1, in addition to the side walls consist of the walls 24 forming the roof of the chamber. These are sloped downwardly and inwardly from the 70 outside toward the central electrode. The blast passing through the ports strikes the side walls and is thrown against the sloping walls 24, and is by them deflected downward and inward against the electrode and 75 100 105 110

through the spark gap. This tends to scour or keep clean both electrodes. The rush of gas past the opening 10 tends to draw out the gas from the chamber 6, and thus 5 tends to keep that chamber clean. The action in the scouring chamber is assisted by the lower walls or floor 25, which slope downwardly and inwardly to the spark gap. Moreover, the blast from the explosion 10 through its contact with the side walls of the ports 23 and with the side and top walls of the scouring chamber, is very considerably reduced in temperature so that when it strikes the electrodes it has less tendency 15 to heat them. In this way undue heating of the electrodes and pre-ignition are prevented.

Because of the efficiency of my improved spark plug in dissipating heat, I find that 20 I can treat the mica with linseed oil, as by immersion in a bath of the same, without any danger of the mica, in the practical use of the spark plug, absorbing engine oil and carbon, and without any danger of the 25 linseed oil in the mica becoming itself carbonized. The presence of the linseed oil in the mica prevents it from absorbing engine oil or carbon which, as well known, would reduce the resistance of the mica to 30 high tension current and reduce its heat conductivity. As is well understood, excessive heat tends to carbonize linseed oil in mica and this has heretofore prevented the successful use of linseed oil with mica in spark 35 plugs for use in high speed or high compression motors. By my improvement, however, linseed oil can be used in spark plugs for use in such motors.

The downwardly and outwardly sloping 40 surfaces 17 projecting below the electrodes, serve to protect them and also assist in drawing oil away from them.

Fig. 4 merely represents a modification in which, in place of the cone or ring 14, 45 Fig. 1, made of brass, I use a somewhat larger cone or ring 26 made of mica. The mica is compressed between the follower 11 and the spindle 2 in the same manner as described for the brass ring 14 and for the 50 same purpose. In Fig. 4 also I have shown the electrode 1 as enlarged at its lower end 27 so as to form a larger circular spark plug.

Fig. 5 represents a modification in which I have dispensed with the cooling chamber 55 19 of Fig. 1, and substituted in its place exterior radiating projections, shown in Fig. 5 as ribs 28. Fig. 6 is like Fig. 5 except that it omits the radiating projections 28.

60 My improved spark plug, especially in its preferred form, is peculiarly well suited to the engines of high compression motors as it is able to withstand the strains and high temperatures encountered in such engines. 65 It dissipates the heat rapidly, the electrode

surfaces are kept bright and clean, and the parts kept in efficient condition, so that the spark plug, even under the most trying conditions, is durable or has long life, and is 70 very efficient.

In the form of my improvement shown in the drawings, Fig. 1 is the most efficient and is best adapted for high compression motors such as Liberty motors, and other motors 75 encountered in aviation, where the heat developed is very great. Fig. 5 represents the form next efficient, and is adapted for aeroplane motors of less power where the heat developed is less in amount, and that shown in Fig. 6 is adapted more especially for automobile engines where the heat developed is considerably less. 80

Between the lower section of mica and the lower surface of the follower 11 immediately above it, I preferably leave a small 85 circular space shown at 30 in Fig. 1. This circular space surrounds the lower part of the piece 14. I find that in practice the continued poundings of the explosions on the lower part of the spindle tends to force up 90 the brass ring 14, and thus loosen the joint between the mica and the spindle. I have found that this trouble can be obviated by providing a small gap such as shown at 30 in Fig. 1. The hammering of the explosions, when such a gap is present, causes the lower part of the mica to force the brass 95 piece slightly upward tending to keep the joint tight at all times.

What I claim as new and desire to secure 100 by Letters Patent, is:

1. In a spark plug the combination of an electrode, a chamber surrounding the electrode near its end, having surfaces comprising its roof, floor and walls, inclined to one 105 another and adapted to receive blast from the explosion and deflect it inwardly and downwardly against the end of the electrode and through the spark gap, and ports through the floor of the chamber connecting 110 the latter with the cylinder when the spark plug is in position, and inclined so as to admit the blast from the explosion in the cylinder into the chamber and to direct it against a portion of the said inclined surfaces of the chamber, whereby blast from the explosion will be admitted into the chamber and be deflected inwardly and downwardly against the end of the electrode and through the spark gap. 115

2. In a spark plug the combination of a central electrode, a chamber surrounding the electrode near its end having surfaces comprising its roof, floor and walls, inclined to one another and adapted to receive blast 125 from the explosion and deflect it inwardly and downwardly against the end of the electrode and through the spark gap, the floor of the chamber having near its center a ring electrode surrounding the end of the 130

- central electrode, and ports through the floor of the chamber connecting the latter with the cylinder when the spark plug is in position, and inclined so as to admit blast 5 from the explosion in the cylinder into the chamber and to direct it against a portion of the said inclined surfaces of the chamber, whereby blast from the explosion will be admitted into the chamber and be deflected 10 inwardly and downwardly against the end of the central electrode and through the spark gap.
3. In a spark plug the combination of a central pin electrode having a cylindrical body of relatively large size and a reduced end portion of relatively small size at the spark gap, a chamber surrounding the electrode near its end having surfaces comprising its roof, floor and walls, inclined to one 15 another and adapted to receive blast from the explosion and deflect it inwardly and downwardly against the end of the electrode and through the spark gap, the floor of the chamber having near its center a ring 20 electrode surrounding the end of the central electrode, and ports through the floor of the chamber connecting the latter with the cylinder when the spark plug is in position, and inclined so as to admit blast from the explosion in the cylinder into the chamber and to direct it against a portion of the said inclined surfaces of the chamber, whereby blast from the explosion will be admitted 25 into the chamber and be deflected inwardly and downwardly against the end of the central electrode and through the spark gap.
4. In a spark-plug the combination of a central electrode, a chamber surrounding the electrode, the floor of the chamber forming near its center a ring electrode surrounding the end of the other electrode, ports extending upwardly and outwardly through the floor of the chamber adapted, when the spark-plug is in position, to admit blast 30 from the explosion into the chamber and deflect it against the outer side walls of the chamber, the roof and floor of the chamber sloping downwardly and inwardly to receive and deflect said blast against the central 35 electrode and through the spark gap.
5. In a spark-plug the combination of a central electrode, a chamber surrounding the electrode, the floor of the chamber forming near its center a ring electrode surrounding the end of the other electrode, ports extending upwardly and outwardly through the floor of the chamber adapted, when the spark-plug is in position, to admit blast 40 from the explosion into the chamber and deflect it against the outer side walls of the chamber, and surfaces in the chamber sloping downwardly and inwardly to receive and deflect said blast against the central 45 electrode and through the spark gap.
6. In a spark-plug an electrode, a chamber surrounding the electrode closed to the atmosphere, an outer cooling chamber surrounding the closed chamber and provided with ports opening into the atmosphere.
7. In a spark-plug the combination of a central electrode, a cooling chamber, closed to the atmosphere, surrounding the upper portion of the electrode, and having its walls converge inwardly and downwardly to leave a small air gap between them and the electrode, a chamber surrounding the lower portion of the electrode and having its upper walls slope downwardly and inwardly to said air gap, and provided with ports in its lower walls adapted, when the spark-plug is in position, to admit blast from the explosion into the chamber, whereby the blast will be forced downwardly and inwardly against the electrode and past the said air gap and will thereby draw gas 55 downwardly from the cooling chamber.
8. In a spark-plug the combination of a central pin electrode, and a surrounding metallic piece having an opening at the center for the pin electrode, said piece having its lower surfaces sloping downwardly and outwardly, and its upper surface sloping upwardly and outwardly.
9. In a spark-plug the combination of a central metallic spindle, insulating material surrounding the upper part of the spindle, and a ring of soft metal compressed around the insulating material to make a gas-tight joint around the spindle.
10. In a spark-plug the combination of a central metallic spindle, insulating material surrounding the upper part of the spindle and a ring of soft heat-conducting metal compressed around the insulating material to make a gas-tight joint around the spindle 100 and aid in dissipating heat.
11. In a spark-plug the combination of a central metallic spindle, insulating material surrounding the upper part of the spindle and a ring of compressible material compressed around the insulating material to make a gas-tight joint around the spindle.
12. In a spark-plug the combination of a central electrode, a cooling chamber, closed to the atmosphere, surrounding the upper portion of the electrode and having its walls converge inwardly and downwardly to leave a small air gap between them and the electrode, a chamber surrounding the lower portion of the electrode, ports through the floor of the latter chamber extending upwardly and outwardly, to admit blast from the explosion into the chamber, and surfaces in said chamber adapted to direct the blast 110 downwardly and inwardly against the electrode and past the said air gap, whereby gas will be drawn from the cooling chamber and the surfaces of the electrodes will be cleaned and cooled.
13. In a spark plug the combination of a 115

- central electrode, a chamber surrounding the upper part of the electrode having walls, made of a substance of high heat conducting capacity, converging inwardly and downwardly to leave a small air gap between them and the electrode, an outer cooling chamber provided with ports opening into the atmosphere and surrounding the first mentioned chamber, a scouring chamber surrounding the lower part of the electrode, ports through the floor of said chamber extending outwardly and upwardly and adapted to admit blast from the explosion into the scouring chamber, and surfaces in the scouring chamber shaped so as to direct the blast inwardly and downwardly against the electrode and through the air gap.
14. In a spark plug the combination of a central electrode, a cooling chamber closed to the atmosphere surrounding the upper portion of the electrode and having its walls converge inwardly and downwardly to leave a small air gap between them and the electrode, a scouring chamber surrounding the lower portion of the electrode, and means for admitting blast from the explosion into the last mentioned chamber and directing it inwardly and downwardly against the electrode and through the air gap between it and the other electrode.
15. In a spark plug the combination of a central spindle, insulating material surrounding the upper part of the spindle, a cone-shaped ring of compressible material compressed around the insulating material to make a gas-tight joint around the spindle, a follower with sloping walls fitting around the cone-shaped ring, and a lower section of insulating material surrounding the spindle and abutting against the lower end of said ring, the said insulating material and the said follower being so shaped and arranged as to leave a circular gap between their upper and lower surfaces.
16. In a spark plug the combination of a central spindle, insulating material surrounding the upper part of the spindle, a cone-shaped ring of soft heat-conducting metal compressed around the insulating material to make a gas tight joint around the spindle, a follower with sloping walls fitting around the cone-shaped ring, and a lower section of insulating material surrounding the spindle and abutting against the lower end of said ring, the said insulating material and the said follower being so shaped and arranged as to leave a circular gap between their upper and lower surfaces.
17. In a spark-plug the combination of a central pin electrode and a surrounding circular electrode having an opening at the center for the pin electrode, said central pin electrode having a cylindrical body of relatively large size and a reduced end portion of relatively small size projecting into the opening in the surrounding electrode to form a spark gap, and said surrounding electrode having surfaces sloping upwardly and outwardly from the spark gap, and surfaces sloping downwardly and outwardly from the spark gap.

In testimony whereof, I have signed my name to this specification.

CHARLES W. BREWSTER.
